UNITED STATES PATENT OFFICE

137,121

DESIGN FOR A GRINDING MACHINE

John C. Wilson, Springfield, Ohio, assignor to
The Thompson Grinder Company, Springfield,
Ohio, a corporation of Ohio

Application May 18, 1942, Serial No. 106,941

Term of patent 14 years

To all whom it may concern:

Be it known that I, John C. Wilson, a citizen of the United States residing at Springfield, in the county of Clarke and State of Ohio, have invented a new, original, and ornamental Design for a Grinding Machine, of which the following is a specification, reference being had to the accompanying drawings, forming a part thereof wherein:

Figure 1 is a perspective view of a grinding

machine showing my new design, the view being taken from the front and to the left end;

Figure 2 is a perspective view thereof taken from the front and to the right end;

Figure 3 is a perspective view taken from the rear and to the right end.

I claim:

The ornamental design for a grinding machine, substantially as shown.

JOHN C. WILSON.
